(57) **CLAIM**

The ornamental design for a headphone, as shown and
described.

DESCRIPTION

FIG. 1 is a perspective view of a headphone showing my new
design in an open position;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

FIG. 8 is a bottom perspective view of the headphone of FIG.
1 in a closed position;

FIG. 9 is an opposite side end elevational view of FIG. 8
thereof;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a perspective view of the headphone of FIG. 1 in an
open position, wherein the cord is enclosed from the slit
formed along the elongated connecting part; and,

FIG. 16 is a perspective view of a headphone of FIG. 1 in an
open position, wherein the cord is extracted from the slit
formed along the elongated connecting part.

The portions indicated in broken lines are for illustrative
purposes only and form no part of the claimed design.

The broken away lines in the drawing disclosure indicate
indeterminate length of the cable connected to the headphone,
which is not claimed.
